UNITED STATES PATENT OFFICE.

CLARENCE H. KEEHN, OF INDIANAPOLIS, INDIANA.

CABLE-CODE SYSTEM.

970,716.

Specification of Letters Patent. Patented Sept. 20, 1910.

Application filed October 19, 1908. Serial No. 458,546.

To all whom it may concern:

Be it known that I, CLARENCE H. KEEHN, a citizen of the United States, residing at Indianapolis, in the county of Marion and State of Indiana, have invented certain new and useful Improvements in Cable-Code Systems, of which the following is a specification.

At the present time cable and telegraph companies permit the transmission of code messages comprised of non-dictionary words not exceeding ten letters each if they are pronounceable in syllables in accordance with the usual rules of pronunciation of any of the principal modern languages.

In sending code messages, however, some means need to be ordinarily provided for checking the accuracy of transmission of the message and that is ordinarily done by assigning to each of the various words a distinguishing numerical value which can be indicated as a total by a sentence, word or letter occupying a predetermined position either relative to words or relative to groups of words in the message, or relative to the entire message itself.

The object of my present invention is to provide an improved system of coding which can be readily applied in an almost unlimited number of forms to any desired business, the arrangement being such that pronounceable words of ten letters may be formed of pronounceable syllables of one or more letters each, of which letters or sub-combinations of letters may be given an arbitrary meaning predetermined by a previously prepared code table and wherein the previously agreed-upon letter or letter group, (either the final letter group or letter of each word, or a letter or letter group occupying a predetermined position in the complete message), shall be used as a check, each letter used in the system being given preliminarily a definite numerical value, and the value of the checking letter or letter group being determined by a previously agreed-upon table.

In practice I find it desirable, in assigning the numerical values to the several letters used in the system, to assign the numerical value to the letters corresponding to their numerical position in the alphabet, thus permitting easy memorization of the numerical values of the several letters. For

the check table the vowels are preferably arranged in their usual alphabetical arrangement on one side of a checker board table and the consonants arranged on the adjacent side in the same order, as shown in Figure 1. As many codes as may be desired can be built up on this theory, each particular code sheet being designated by the first letter or syllable of the first word or by any other predetermined designating portion of the transmitted message.

The accompanying drawings illustrate my invention.

Figs. 1, 2 and 3 are different codes or code sheets; Fig. 4, a numerical or quantity code; Fig. 5 a code-sheet designating code, and Fig. 6 an example of the message prepared under the code indicator shown in Fig. 5, said figure also including extracts from the various tables used in the preparation of such message.

In order to illustrate the theory of my invention I give herewith a plurality of examples of different codes constructed in accordance with the theory thereof. In Fig. 1 I have illustrated the skeleton of a code-sheet in which the first letter of the first word will always be a consonant thus indicating that the message is to be translated in accordance with the code of Fig. 1. This first letter will also be used as a part of the message.

The code illustrated in Fig. 1 is especially designed for transmission of messages relating to provisions and each word of ten letters is a complete sentence and check therefor. The first letter designates the buyer's name and also designates the table from which the decoding is to be made. The second letter gives shipping directions, the third letter quantities, the fourth and fifth letters combined indicate articles, the sixth and seventh letters combined indicate price, the eighth letter indicates time of shipment, and the ninth and tenth letters give the check. It will be noticed that the arrangement of the various letters, as to vowels and consonants is such as to produce a pronounceable word, no matter what the combination may be. It is also to be understood that in the two-letter groups all of the consonants may be successively combined with all of the vowels. By this arrangement it is possible, in a single word of ten letters, to

give a complete sentence and an accurate check for that sentence. Of course as many words of ten letters may be contained in a single message as may be desirable in order to give further complete directions in each word to the same addressee. For instance, a cablegram containing the two words "Codbebifici-Fefbucidvi" would be decoded as follows:

10 C O D B E B I C - F I F E F B U C I D VI
3 15 4 2 5 2 9 3 43 6 5 6 2 21 3 9 4 56

Upon receipt of this message the addressee first makes sure of the check. In the first word the check letters are FI and referring 15 to FI in the check table 43 is found as the check number. Adding up the numerical positions of the first eight letters of the word it is found that the check is correct. The check syllable of the second word is VI 20 and reference to the check table gives VI a value of 56, while an addition of the numerical values of the first eight letters of the word confirms the check. Thereupon the addressee would turn to the code sheets 25 forming the Example 1 (the transmitted word beginning with a consonant) and would decode the first word as: "Will sell Fr. Brants 3d/s-1%, Cif. Antwerp via Baltimore, ten boxes short clear backs, salt, 30 17/18 lb. avg., Fr. 61 1.8, prompt." (The 61 francs being understood as the current denominative price and the "will sell" being also understood.) And would decode the second word as: "Will sell H. Collin van 35 der Borgh, 3d/s-1%, Cif. Antwerp via Red Star Line fifteen boxes short fat backs 8/10 lb. avg. Fr. 61 3.4 this month."

The addressee may use the same table in reply, the words "Offer declined will buy" 40 being understood, in place of "Will sell" which are understood when the addresser is cabling.

It will be readily understood that an almost unlimited number of different code 45 sheets may be produced in accordance with the theory of my invention by varying the number of letters in each group and changing the relation of the groups. For instance, in Fig. 2, I have indicated a code sheet 50 available for replies to inquiries as to when, where, and to whom certain deliveries can be made. In this form each word begins with AI as an indicator for the table to be used in decoding; the 3rd, 4th and 5th letters give the name of consignee or buyer; the 6th and 7th letters indicate the port; the 8th and 9th letters indicate time or manner of delivery, and the 10th letter is the check. In this form the letters comprising the 1st 55 to 9th letters inclusive of each word are (for checking purposes) given a numerical value corresponding to their position in the alphabet, as in the preceding illustration; these values are added together; the hundreds and tens discarded, and the units used

as a check in accordance with the one-letter check table.

In Fig. 3 I illustrate a code sheet for a two-word message, the first word containing the decoding-table indicator, and the second 70 word containing, as its final syllable, (or two-letter combination) the check. In this form the message letters have a numerical value, as in the preceding examples and the check table shown in Fig. 1, the hundreds being discarded. 75

The same principle may be readily applied to a figure-value or quantity table, and in Fig. 4 I have illustrated such a table having, in a word of ten letters, a capacity from 80 0 to 99,999,999, and a check.

For example AB AB AB AC RA would be decoded by giving the first eight letters their numerical alphabetical values, adding, and comparing with the check value of the 85 last two letters. If the check is correct, as shown above, comparison of the first eight letters with the value table would give 0 0 0 0 0 0 0 1 or 1.

Similarly A X U Z A N A D UQ would 90 be decoded as follows. First adding the position values of the first eight letters we have, 1 (A), plus 24, (X), plus 21 (U), plus 26 (Z), plus 1 (A), plus 14 (N), plus 1 (A), plus 4 (D) equals 92, therefore the check 95 UQ (placing the vowel first.) Comparison with the value table then gives AX equals 18, UZ equals 99, AN equals 10, AD equals 02, thus giving by a single word, the number 18,991,002, and an accurate check therefor. 100

In the use of a code constructed in accordance with this invention, and also in the use of other codes, it is often necessary, where the code covers a considerable range, to arrange the code in a plurality of sub-codes or 105 "code-sheets" each sub-code or code-sheet having a peculiar designation differentiating it from other sub-codes or code-sheets, and it is therefore necessary to provide means to enable the receiver to be advised of 110 the particular sub-codes or code-sheets which may have been used by the sender in the production of any particular message. I have therefore developed means by which, in a single word of ten letters, there may be 115 given a complete statement of all of the code sheets which may have been used in a particular message, indicating at the same time, in the same word, the order in which said code sheets are to be used in decoding 120 the message and also giving a check which will check the accuracy of the table designation. This portion of the code is completely given in Fig. 5 of the drawings.

It will be seen that the code-sheets are 125 first supposed to have been grouped into four groups each group comprising seven code-sheets or code-tables. It will of course be understood that if a greater number of tables comprises the entire code then each 130

group will be augmented, the designating number of the augmenting sheets increasing in geometrical proportion. For instance in the table given the seven code sheets of group A are separately designated as "A1", "A2", "A4", "A8", "A16", "A32", "A64", and therefore additional sheets would be numbered "A128", etc.

The first word of the cablegram will be 10 the word used for designating the tables or code-sheets which were used by the sender in compiling the message. The first two letters of the first word indicate the particular tables of group A which have been used and 15 their order of use. The third and fourth letters of the first word indicate the particular tables of group B and their order; the fifth and sixth letters indicate the used tables of group C, and the seventh and eighth 20 letters indicate the tables of group D. The manner of use is as follows: Suppose that the sender has used, in the compilation of his message the following tables, to - wit: A2 which is a two-letter table (*i. e.* all code 25 portions comprise only two letters); A8, a three-letter code; A64 a four-letter code; B4, a three-letter code; B16, a five-letter code; B64, two-letters; C1, eight letters; C32, two letters; D1, three letters; D2, four 30 letters; D4, three letters; D8, two letters; D16, four letters; D32, eight letters; D64, two letters. The first word of the cablegram will be made up in the following manner. A2 plus A8 plus A64 equals A74. 74 in the 35 value table is "OS" and therefore "OS" will be the first two letters of the first word; B4 plus B16 plus B64 equals B84 and 84 is "UG"; C1 plus C32 equals C33 and 33 is "ER"; D1 plus D2 plus D4 plus D8 plus 40 D16 plus D32 plus D64 equals D127 and 127 is "SH", so that the first eight letters of the first word of the message will be "Osugersh". Referring then to the check table and the numerical position table, 45 which are exactly like those already described, we find the numerical positions of these first eight letters to be

O	S	U	G	E	R	S	H
15	19	21	7	5	18	19	8

50 and these numerical values added together equal 112. Discarding the figure in the hundreds column, as that may be understood, and referring to the check table we find "12" is "AQ" (reading the vowel first) 55 which will form the ninth and tenth letters of the first word of the cablegram so that the first word of the telegram will be "Osugershq".

In decoding the message the receiver (after 60 checking the correctness of the word in the manner already described) takes the first two letters "OS" of the first word and finds "OS" to be 74. He will thereupon resolve 74 into its highest arithmetical components 65 in geometrical progression, that is 74 minus

64 equals 10; 10 minus 8 equals 2, thus showing that tables A2, A8 and A64 are to be used in the order given. Table A2 to be used in decoding the first two letters of the message (of course following the first word) 70 table A8 used in decoding the next three letters; table A64 to be used in decoding the next four letters. In the same manner the succeeding pairs of letters of the designating word will be resolved in the manner already described to indicate the particular portions of the groups to be used. In decoding the message no attention whatever is paid to word formation, the letters of the message being decoded in regular order in 80 groups determined by the order of the tables, the word formation being purely arbitrary to comply with the rule of the cable companies requiring that arbitrary code words shall not exceed ten letters each. 85

In the example given at the beginning of Fig. 6 of the drawings I have indicated a message made up in accordance with the code indicator shown in Fig. 5 as already described. The first word of this message 90 is "Osugershq", as given above, and indicates the various tables which have been used and their order of use, as will appear. The next 5 words and the first six letters of the seventh word, to-wit: "Bobadbubub" 95 "Agbebabbub" "Acbagbuboc" "Agbebicace" "Cebebibacbefadbo" form the body of the message. The "CH" of the seventh word is understood to mean "check," to-wit, the ending of the message and the beginning of the check so that the last two letters of the seventh word and the whole of the eighth word are used as checks in a manner to be described. The manner of resolving the first word into its components in order to determine the particular tables which were used to make up the message is clearly indicated in Fig. 6 it appearing, as already described, that tables A2, A8, A64, B4, B16, B64, C1, C32, D1, D2, D4, D8, D16, D32, 100 and D64, were used.

Bearing in mind that the word division of the message is merely for the purpose of complying with the rules of the cable company and is to be ignored wholly in decoding, and bearing in mind that the tables are to be used in their regular order, the message will be decoded as follows:

Tables of A group.

Bo (A2)=Sales today 75 packages.

Bad (A8)=Market is dull.

Bubu (A64)=Stock on hand 404 packages.

Tables of B group.

Bag (B4)=Stock includes last consignment No. 4.

Bebob (B16)=We recommend shipment to Liverpool of 75 packages by express. 130

Bu (B64)=Total imports at Liverpool for last week 5300 packages.

Tables of C group.

5 Bacbagbu (C1)=Ship to J. K. Addison & Co. Bixby weekly this month 100 pails of lard.

Bo (C32)=Danish imports 1200.

Tables of D group.

10 Cag (D1)=Market for Danish lower quoted 26/6.

Bebi (D2)=You may draw on account at 60d/s London for £1500.

15 Cac (D4)=Mr. Smith will sail Celtic.

Ec (D8)=What is your opinion of prices for January?

Bebi (D16)=What is your opinion of receipts for February?

20 Bacbefad (D32)=Ship to J. K. Addison & Co. Lincoln, this week 3 boxes of hams 12/14 average.

Bo (D64)=Pail lard stored at Liverpool selling 25/6.

25 The check is ascertained in accordance with the word group to-wit, the individual letters of the words are given their numerical position value in accordance with the table of numerical positions found in Fig. 1. The second word "Bobadbubub" totals 72 and therefore the first check syllable following the "CH" is "OQ" as determined by the check syllable table shown in Fig. 1. Correspondingly the checks are 30 as follows:

Agbebobbub=59=IY.

Acbagbuboc=57=IW.

Agbebicace=38=EX.

Cbebibaoc=29=EM.

40 Efadbo=33=ER.

It will be understood that there have been omitted from Fig. 6 tables of each group which were not used in the particular message illustrated.

45 It will also be understood that if none of the tables of group A are to be used, then the first two letters of the indicator word would be, in accordance with the table forming part of Fig. 5, the letters AB. And 50 these same letters would be used in their it would be apparent that none of the tables of any group were to be used. For instance if the first word should be "Abavababeq" it would be apparent that none of the tables 55 in groups A, C and D had been used and that, AV indicated the use of only table B16 while the EQ gives the check of the indicator word.

I claim as my invention:

60 1. A code system wherein letters or groups of letters of less than a permissible word-number, and capable of being added together into transmittable words, are given arbitrary meanings and checked by having

each individual letter possess a predetermined check value which, combined can be indicated by one or more letters.

2. A code system wherein letters or groups of letters of less than a permissible word-number, and capable of being added together into transmittable words, are given arbitrary meanings and checked by having each individual letter possess a predetermined check value which, combined can be indicated by one or more letters combinable 75 with the checked letters.

3. A code system wherein the individual letters thereof are assigned identifying number values which can be accumulated and indicated as a total by a letter or letters 80 having a predetermined value.

4. A code comprised of a plurality of code sections divided into groups with the several members of each group separately designated by numbers in geometrical progression, an arithmetically progressive table comprising as many multi-letter indicators as the arithmetical sum of the designating numbers of the largest group, the said multi-letter indicators each comprising letters 90 pronounceably combinable with any other multi-letter group whereby a word composed of a plurality of said multi-letter groups will serve to designate any possible selection of tables in the several groups. 95

5. A code comprised of a plurality of code sections divided into groups with the several members of each group separately designated by numbers, an arithmetically progressive table comprising as many indicators as the arithmetical sum of the designating numbers of the largest group, the said indicators each comprising members codically combinable with any other indicator whereby a transmittable indicator will 100 serve to designate any possible selection of tables in the several groups.

6. A code comprised of a plurality of code sections divided into groups with the several members of each group separately designated by numbers, in geometrical progression, an arithmetically progressive table comprising as many indicators as the arithmetical sum of the designating numbers of the largest group, the said indicators each 110 comprising members codically combinable with any other indicator whereby a transmittable indicator will serve to designate any possible selection of tables in the several groups. 115

In witness whereof, I have hereunto set my hand and seal at Indianapolis, Indiana, this 9th day of October, A. D. one thousand nine hundred and eight.

CLARENCE H. KEEHN. [L.S.]

Witnesses:

ARTHUR M. HOOP,

THOMAS W. McMEANS.
